WIRELESS AERIAL

Norman Wells, Ardeevin, Epsom Downs, England, assignor to Radio Corporation of America, a corporation of Delaware

Application April 19, 1937, Serial No. 137,703
In Great Britain April 29, 1936

2 Claims. (Cl. 250—33)

This invention relates to aerials for wireless signalling and more particularly to aerials of the type sometimes termed "inverted" aerials, i. e., aerials operating as half wave aerials but having a so-called artificial "top" terminating the upper end of a vertical aerial section.

The invention is illustrated in and further explained in connection with the accompanying diagrammatic drawing in which Figures 1, 2 and 10 3 illustrate different forms of half wave antennas for the purpose of explaining the present invention. Figure 4 illustrates an embodiment of the present invention, while Figures 5 and 6 illustrate modifications thereof.

15 Referring to Fig. 1, it is usual at the present time to constitute (in the manner shown in Fig. 1) an aerial operating as a half wave aerial by a vertical down lead 1 having an artificial "top" in the form of a horizontal conductor 2a, 2b 20 which is symmetrically disposed with relation to the down lead. This well known type of arrangement is satisfactory if the length of the down lead is of the order of three-eights or more of the working wavelength, that is to say, when the 25 horizontal "top" 2a, 2b is equivalent to an artificial extension of the order of one-eighth or less of the working wavelength so as to make the total aerial length electrically half the working wavelength. If, however, the down lead is less than 30 approximately three-eights of a wavelength long and particularly when it is one-quarter or less of a wavelength long, the dimensions of the horizontal artificial "top" become such that substantial radiation takes place therefrom. The dimensions marked on Fig. 1 illustrate a typical case 35 of this nature, λ in Fig. 1 representing the wavelength. It has been shown that for the case illustrated in Fig. 1, where the vertical down lead is 0.25λ , and 2a and 2b are each of about the 40 same length, the radiation resistance due to additional and unwanted radiation from the artificial "top" amounts to about 9 ohms. As the radiation resistance of an ideal aerial of this type is 32.4 ohms, it will be appreciated that 9 ohms 45 45 radiation resistance due to unwanted radiation represents an appreciable loss of energy.

Various expedients have been suggested to meet this difficulty. For example, it has been suggested to fold back each half 2a or 2b of the 50 horizontal wire constituting the artificial "top" in zig-zag fashion in the manner represented in Fig. 2 (where the supporting masts are not shown), the two zig-zag halves of the "top" being similar and consisting of wire arranged in a horizontal plane and zig-zagging in the same general

direction for both halves of the "top." This known arrangement in effect reduces the overall length of the "top" as compared to that which would be obtained where a simple horizontal wire used as a "top." The arrangement has, however, the serious defect that symmetry is lacking, since in plan view the whole "top" lies to one side of the junction between the vertical down lead and the horizontal "top." Moreover, the arrangement does not give, by any means, the most effective use of the conductor, as regards the distribution of inductance and of capacity.

Fig. 3 shows another known expedient. Here the central portion of the "top" consists of a single wire 2c, 2d which divides or spreads out at 15 each end into two parallel separated wires 2e or 2f. In this arrangement the central conductor 2c, 2d is relatively inductive while the portions 2e, 2f are relatively capacitive. This arrangement too, lacks efficiency.

According to this invention, a half wave aerial of the kind comprising a vertical or substantially vertical down lead (which is preferably though not necessarily a multiple wire or cage down lead 20 artificial "top", is characterized in that the said "top" is symmetrical and consists of a plurality of wires lying in a substantially horizontal plane, or of a substantially horizontal cage of wires connected to the down lead through two equal, oppositely extending horizontal connections 25 which form part of said cage and which meet at the junction point to said down lead, the outer ends of said connectors being symmetrical with regard to the whole cage or plurality of wires 30 which constitute the "top."

Referring to Fig. 4 which shows one way of carrying out this invention, the vertical down lead 1 of an aerial of the kind in question is connected to the middle point 3 of a horizontal wire 4 which is between and equi-distantly spaced 40 from two further wires 5, 6 of equal length and coplanar therewith. The outer ends of all three wires 4, 5, 6 are joined together, as shown, by two cross wires 7, 8 which are parallel to one another and at right angles to the wires 4, 5, 6 which 45 they join. To give typical dimensions: For a wavelength of 98 meters, the length of lead 1 might be 65 feet; the length of each of the wires 4, 5, 6 might be 60 feet; and the length of each of the wires 7, 8 might be 4.5 feet. The arrangement thus dimensioned operated efficiently as a half wave aerial on 98 meters. The instantaneous relative directions of current are indicated in Fig. 4 by arrow heads.

As will be appreciated the arrangement of Fig. 55

4 may be regarded as a half wave T aerial with a down lead of electrical length between $\frac{1}{8}\lambda$ and $\frac{3}{8}\lambda$ provided with a horizontal substantially non-radiating artificial "top" consisting of a plurality 5 of horizontal wires symmetrically disposed about the upper end of the down lead and so arranged that, in effect, the outer conducting paths are folded back upon the inner conducting paths.

In a slight modification (illustrated in Fig. 5) 10 of the embodiment of Fig. 4, the two outer wires 5, 6 between which the middle wire 4 is positioned are not continuous, but each has a central portion removed at 5a and 6a.

It should be noted that in Figs. 4 and 5, which 15 are simplified figures, the downleads are represented as simple wires. As already stated, however the downlead will, in practice, generally be constituted by a multiple wire down lead or by a cage of wires.

20 It should be pointed out that a "top" provided in accordance with this invention is not a simple capacity "top" such as would be employed for a long wave aerial, for the invention is concerned with the provision of an artificial extension requiring both inductance and capacity. In fact 25 the essence of the invention may be said to consist in the employment of symmetrical single conductors where current is of high amplitude, i. e., when inductance is more effective and the provision 30 of symmetrical branching out into parallel conductors where current is of low amplitude and potential is rising, i. e., where capacity is more effective. The reality of this distinction may be shown by an experiment which has been performed. An embodiment, as shown in Fig. 4 and 35 dimensioned as hereinbefore specifically described, was modified as shown in Fig. 6 (which is not in accordance with this invention) by providing a conductive strip 9 centrally across the three 40 wires 4, 5, 6, this conductive strip thus joining together the middle points of all three wires and virtually transforming the artificial "top" into a simple "capacity top", such as is well known for long wave aerials. With the "top" modified in 45 this manner, it was found necessary in order to cause the aerial as a whole to operate as a half wave aerial on 98 meters, to make the overall length of the top 121 feet for the same length (65 feet) of down lead and the said width (4.5 50 feet) of "top."

It will now be seen that the invention provides in an aerial of the kind referred to a simple, symmetrical, compact and almost entirely non-

radiating "top" wherein inductance and capacity are properly apportioned.

It will be appreciated that the invention may be applied equally to so-called "anti-fading" aerials, i. e. to aerials which are extended vertically downwards below what would otherwise be the half-wave terminal in order to obtain an improved vertical polar characteristic. 5

The invention is not limited to the precise arrangements described with reference to and illustrated in Figs. 4 and 5. For example, in carrying out the invention, there may be applied to a substantially vertical aerial a "bottom" similar to and additional to a "top", as hereinbefore described, the "bottom" also aiding in obtaining a 10 desired current distribution in the substantially vertical member. Thus the arrangements of Figs. 4 and 5 might be modified by providing at the foot of the downlead 1 (in each case) a terminating circuit or "bottom" like the "tops" shown 15 in the respective figures. Such a modification would be useful as an aerial for aircraft navigation aiding purposes wherein a current node about half way up a vertical radiator is required 20 in order to give radiation emanating at an angle 25 from the horizontal.

What is claimed is:

1. A half wave T aerial having a down lead which is in length not less than one-eighth nor more than three-eighths of the length of the 30 working wave, said aerial having a horizontal substantially non-radiating top comprising a central conductor and a pair of spaced axially aligned conductors arranged on each side of said central conductor and parallel thereto, all of said 35 conductors lying in a common horizontal plane, the outer ends of a wire from each of said pairs of conductors and the ends of said central conductor being connected by a cross connector at their adjacent ends. 40

2. A half wave T aerial having a down lead which is in length not less than one-eighth nor more than three-eighths of the length of the working wave, said aerial having a horizontal substantially non-radiating top comprising a 45 central conductor and a pair of spaced axially aligned conductors arranged on each side of said conductor and parallel thereto, all of said conductors lying in a common horizontal plane, one end of a conductor end from each of said pairs of 50 conductors and the ends of said central conductor being connected by a cross connector at their adjacent ends.

NORMAN WELLS.
